CONSOLE

Ward J. O'Connor, Bayonne, N. J., assignor to
The Lummus Company, New York, N. Y., a corporation of Delaware

Application November 12, 1949, Serial No. 5,995

Term of patent 7 years

(Cl. D26—5)

To all whom it may concern:

Be it known that I, Ward J. O'Connor, a citizen of the United States, residing at Bayonne, county of Hudson, State of New Jersey, have invented a new, original, and ornamental Design for a Console, of which the following is a specification, reference being had to the accompanying drawing, forming a part thereof.

Fig. 1 is a perspective view of a console, showing my new design;

Fig. 2 is a side elevational view thereof, drawn to a reduced scale;

Fig. 3 is top plan view thereof drawn to a further reduced scale; and

Fig. 4 is a detail vertical sectional view on the line 4—4 of Fig. 3, drawn to the same scale as Fig. 2.

The control elements have been omitted from Figs. 3 and 4 for convenience of illustration.

I claim:

The ornamental design for a console, as shown and described.

WARD J. O'CONNOR.
